Statement

UNITED STATES PATENT OFFICE.

WILLIAM H. GAULKE, OF MILWAUKEE, WISCONSIN, ASSIGNOR TO INDEPENDENT ELECTRIC MANUFACTURING COMPANY, A CORPORATION OF WISCONSIN.

STARTER AND REGULATOR FOR COMPOUND MOTORS.

1,008,811.

Specification of Letters Patent. Patented Nov. 14, 1911.

Application filed February 6, 1911. Serial No. 606,751.

To all whom it may concern:

Be it known that I, WILLIAM H. GAULKE, of Milwaukee, Wisconsin, have invented a Starter and Regulator for Compound Motors, of which the following is a specification.

This invention relates to rheostats or so-called starting-boxes and regulators for compound motors, and the object of the invention is to provide, first, a combined armature and field-current regulator with connections between the two which provides that the field resistance shall at all times be cut out upon the starting of the motor; secondly, to provide an improved form of magnet-armature for the contact-arm; thirdly, an improved form of contact-segment; and fourthly, to provide an improved mechanical design of arm, which shall be simpler, cheaper and stronger than those heretofore used.

Other objects of the invention will appear from the detailed description which follows.

My invention comprises the constructions and combinations which will be hereinafter more specifically described and set forth in my claims.

For the better understanding of my invention I have illustrated two approved forms thereof in the accompanying drawings, wherein—

Figure 1 is a face-view of a regulator provided with my improvements; Fig. 2 is a fragmentary sectional view upon the line 35 2—2 of Fig. 1; Fig. 3 is a perspective view of the speed-regulating arm; Fig. 4 is a perspective view of the magnet-armature; Fig. 5 is a diagram of the electrical connections; Fig. 6 is a face-view of another form of regulator, embodying my improvements; Fig. 7 is a longitudinal cross-section thereof upon the line 7—7 of Fig. 6; Fig. 8 is a side-view upon a larger scale of one of the contact-segments *in situ* to illustrate the 45 slightly convex original form thereof; Fig. 9 is a perspective view of the contact-segment; Fig. 10 is a similar view of the sliding contact-block; and Fig. 11 is a side-view of the starting contact-arm.

50 The reference letters refer each to the same part in each figure of the drawings.

In the first form of the drawings the starting and speed-regulating arcs are on opposite sides of the front face of the face-plate, 55 while in the second form they are disposed

one within the other, making a more compact arrangement. Describing first the former, A designates the face-plate secured to the rheostat-casing by screws a' , and provided with terminals B, C, D and E for connection with the line, armature, and field-wires, as indicated by their legends, and connected to the various elements of the apparatus as will hereinafter more particularly appear. Upon a pivot-post F mounted upon the plate A turn the two contact-arms G and H, the former of which is the starting-arm, and the second the speed-regulating arm. The arm G connects electrically with the contact-segments I, being provided 70 opposite said segments with a movable contact-block J, which is pressed into yielding engagement with the segments by a bar K, through which passes a post M, upon which is a spring L pressed downwardly upon the 75 bar K by a nut m' , as will be more particularly seen from the construction described in connection with the second form (Fig. 7). The contact-block J may for better electrical connection be electrically connected with the 80 arm G by a flexible cable j' , secured upon a screw terminal g' . A handle g^2 is provided on the outer end of the arm, and beyond this the arm G is provided with an extension g^3 , to which is pivotally secured by means of a 85 headed pin or rivet g^4 a small iron plate N, which is the armature for the electromagnet O, this latter consisting of a coil o' , an iron core o^2 , and a support o^3 , which has an iron yoke o^4 forming the opposite magnet-pole 90 to the free end of the core o^2 .

The form of the armature N is shown more particularly in Fig. 4, and it will be seen that this is an improved form of the armature shown in the copending joint application of Julius T. Kalweit and myself, No. 570,915, filed July 7, 1910. The plate N is in this instance provided with a pivot-ear n' which is centrally located between the two poles n^2 and n^3 , the latter being adapted 95 to register with the end of the core o^2 and of the yoke o^4 respectively, and as will be seen said pivot-ear n' is depressed below the top of the plate so as to bring it as nearly central as possible, and it may be somewhat loose upon its pivot, so as in effect to have a limited free swinging movement in all directions, and thus to bring it into perfect contact and alinement with the two magnet poles.

The speed-regulating arm H as shown comprises a simple plate of spring brass, which is mounted directly beneath the arm G, and therefore maintained in parallel alinement, and the end of which is resiliently depressed upon one of the series of contact-buttons P, which are connected to the successive sections of p' of the field-resistance. The arm H may be provided near its free end with a handle h' . The particular feature of novelty with regard to this arm is its connection with the arm G. At one side of said arm near its base there is an upstanding lug h^2 , which extends above the left-hand edge of the arm G in the manner shown; so that the two arms cannot be separated by an angle greater than 90 degrees. As usual a spring Q, the end of which rests upon a post q' , is employed to return the arm G when released to its starting point, shown in full lines in Fig. 1, and when so released it carries with it the arm H in whatever position the latter may be back to its starting point. This is provided in order that all the field resistance may be cut out at the starting of the motor without fail, which, as is well understood, is essential to the proper operation of motors. Moreover I provide means whereby the arm H cannot be advanced at all, until the arm G has been turned up to its terminal position, and all the resistance cut out of the armature, at which point it may be held by the magnet O. This means comprises a spring-clip R secured to the base A by screws r' or the like, and illustrated in side-view in Fig. 2. As shown, this clip is formed with a depression or channel r^2 adapted to engage the edges of the arm H and prevent it from moving, and at the left of this channel is an elevated portion r^3 in the proper position to be struck by a projecting portion of the arm G, said projecting portion being in this case, as illustrated by the dotted-lines, the head on the bottom of a rivet r^8 , and which is used for securing the pieces of the arm together as will be hereinafter described. When the contact-arm G is advanced to its dotted-line position, said projection strikes the convexity r^3 , and depresses the clip R to its dotted-line position, thus releasing the handle H, and permitting it to be advanced. To the right of the channel r^2 is provided an oblique lip r^4 , which is engaged by the edge of the arm H in returning to its starting position in order that it may depress the clip and enter the channel r^2 .

The electrical connections of the apparatus are as shown in Fig. 5, the contact-segments I being connected to the successive segments i' of the armature-resistance as usual, except the extreme left-hand section, which is a blank. The armature terminal C is connected by a lead 11 to the right-

hand segment I, the field-terminal E by a lead 12 to the left-hand abutment P, one line-terminal B by a lead 13 to the pivot-post F, and the other line-terminal D by a lead 14 to one terminal o^5 of the magnet O, 70 while the other terminal o^5 is connected to the armature-resistance i' as shown, with the additional insertion of an extra resistance o^6 for the purpose of reducing the current in the magnet-coil o' , but this is not essential to my invention. The abutment-piece S, surrounded by a rubber cushion s' , is provided to limit the counter-clockwise movement of the arm G. 75

In the second form of the invention a narrow base-plate A' takes the place of the base-plate A, and the elements a', B, C, D, E, F, I, J, K, M, N, O, Q, q', S and s' are the same and similarly disposed to the first form; but the contact-buttons P' for the field-resistance occupy a position concentric with the segment I as shown, and the speed-regulating arm H' has a somewhat different form. In this case no lug h^2 is provided, but instead thereof there is a handle h^3 fixed on an extension at one side of the arm in position to engage the side of the starting-arm G', so that the latter in returning to its starting-position, strikes the handle h^3 and carries with it the arm H'. 90

In operation the arm G' is first moved to its full-line position, and being held thereby by the magnet, the arm H' is next moved up to the position desired to give the required speed. A shoulder h^4 may be provided on the side of the arm H' to engage the cushion s'. 100

The only difference between the arms G and G' is in the location and position of the armature-plate N. In the arm G' the extension g^3 and pin g^4 are omitted. As will be seen from Fig. 11, the arm is built up from two sheet-metal strips g^5 and g^6 , secured together by rivets g^7 , g^8 , g^9 and perforated to receive the screw-post g^{10} of the handle g^2 and the terminal-screw g^1 . The basal end of the strip g^5 is offset as shown at g^{11} , and the two ends perforated as shown to receive the post F; thus giving axial rigidity to the arm in a cheap and effective manner. The space between the ends of the strips g^5 , g^6 is occupied by the spring Q. Near the other end of the arm the lower strip g^6 is offset as shown at g^{12} , so as to provide a wide bearing for the block J, which fits loosely within rectangular apertures g^{13} formed in both strips. This construction of arm is shown in the aforesaid joint application of Julius T. Kalweit and myself, but is not claimed therein, as it constitutes my sole invention. In the second form of the invention the pivot-ear n' of the armature-plate N enters the space between the strip g^5 and the offset g^{12} , having a free movement therein, and is pivoted 130

loosely upon a pin n^4 , so as within a limited angle to have a free angular movement in all directions as previously described. In this case, on account of the relative position of the magnet-poles, the plate N is reversed in position. The form of contact-segment I is also as described in my aforesaid joint application, but with an improvement. Said contact-segment comprises a plate of sheet-metal, shown in the side-view in Fig. 8, and perspective in Fig. 9, whose inner end receives the end of a dowel-pin T seated in a recess a^2 in the face-plate A and provided with a spacing-shoulder t' . The other end of the plate I is secured by a nut u' to the end of a screw-post U, a second nut u^2 of the same thickness as the spacing-shoulder t' being placed under the plate I to hold it level. Now, I have found that in this construction as originally described, in which the plate I was perfectly flat, the nut u' was insufficient to keep the bars tight, and the inner ends thereof were apt to rattle to a slight extent, so that the faces of the contact-segments would not all be perfectly level, but one would rise slightly above the other, and the block J would catch upon the edges thereof and fail to work smoothly. To avoid this difficulty, according to my present invention I form the segments I very slightly convex, as illustrated by perspective view in Fig. 9, and by the dotted-lines i^2 of Fig. 8, this being done without any extra expense by simply grinding away very slightly the edges of the punching die. The convexity thus produced is exaggerated in the drawings to make it visible to the eye, and when the screw u' is turned up tight, it will result in depressing the inner end of the plate I, and holding it in tight connection with the shoulder t' , while at the same time bending it substantially flat as shown.

From the above description it will be readily seen that my invention is not limited to special forms and mechanical constructions such as I have hereinabove shown by way of illustration, but that the principles thereof are expressible in a variety of ways as will be well understood by those skilled in the art; therefore the scope of my claims is to be interpreted in view of such alternative constructions.

Having thus described my invention, what I claim as new and desire to secure by Letters Patent is:

1. In a device of the class described, the combination of two coaxially pivoted contact-arms and two sets of contact-segments with which they coöperate, each of said sets being connected to the successive sections of a resistance, and the terminal end of one resistance being adapted for direct-connection with the armature of an electric motor, and the starting end of the other resistance

being adapted for direct connection with the field thereof; in conjunction with means for operative engagement between the two arms, whereby the former in returning to the starting-point carries with it the latter, and the latter cannot be advanced without advancing the former. 70

2. In a device of the class described, the combination of two coaxially pivoted contact-arms and two sets of contact-segments with which they coöperate, each of said sets being connected to the successive sections of a resistance, and the terminal end of one resistance being adapted for direct-connection with the armature of an electric motor, and the starting end of the other resistance being adapted for direct connection with the field thereof; in conjunction with means for operative engagement between the two arms, whereby the former in returning to the starting-point carries with it the latter, and the latter is held at its starting-point until the former has reached its terminal-point. 80

3. In a device of the class described, the combination of two coaxially pivoted contact-arms and two sets of contact-segments with which they coöperate, each of said sets being connected to the successive sections of a resistance, and the terminal end of one resistance being adapted for direct-connection with the armature of an electric motor, and the starting end of the other resistance being adapted for direct connection with the field thereof; and a projection on the second arm which is adapted to be struck by the first in its return movement, so as to carry the second with it to the starting-point. 90

4. In a device of the class described, the combination of two coaxially pivoted contact-arms and two sets of contact-segments with which they coöperate, each of said sets being connected to the successive sections of a resistance, and the terminal end of one resistance being adapted for direct-connection with the armature of an electric motor, and the starting end of the other resistance being adapted for direct connection with the field thereof; a projection on the second arm which is adapted to be struck by the first in its return movement, so as to carry the second with it to the starting-point, and a retaining-device adapted to engage and hold the second arm in its starting-position 110 and to be acted on by the first arm when in its terminal position to withdraw it from said engagement. 115

5. In a device of the class described, the combination of two coaxially pivoted contact-arms and two sets of contact-segments with which they coöperate, each of said sets being connected to the successive sections of a resistance, and the terminal end of one resistance being adapted for direct-connection 120 with the armature of an electric motor, and the starting end of the other resistance

- tion with the armature of an electric motor, and the starting end of the other resistance being adapted for direct connection with the field thereof; and a device adapted 5 to engage the second arm and hold it in its starting-position, said device being actuated by the first arm in reaching its terminal position to disengage it from the second arm.
6. In a device of the class described, the 10 combination of two coaxially pivoted contact-arms and two sets of contact-segments with which they coöperate, each of said sets being connected to the successive sections of a resistance, and the terminal end of one 15 resistance being adapted for direct-connection with the armature of an electric motor, and the starting end of the other resistance being adapted for direct connection with the field thereof; and a spring-clip adapted 20 to resiliently engage and hold said second arm in its starting position.
7. In a device of the class described, the 25 combination of two coaxially pivoted contact-arms and two sets of contact-segments with which they coöperate, each of said sets being connected to the successive sections of a resistance, and the terminal end of one 30 resistance being adapted for direct-connection with the armature of an electric motor, and the starting end of the other resistance being adapted for direct connection with the field thereof; and a spring-clip adapted 35 to resiliently engage and hold said second arm in its starting position, said spring-clip having an element adapted to be struck

by a part of the first arm in its terminal position and depressed thereby, so as to release said second arm.

8. In combination a contact-segment consisting of a plate having a slight convexity, 40 a face-plate of insulating material, rests for the two ends of said plate, and means for clamping one end of said plate down upon its rest; said clamping means acting to flatten out said convexity and thereby hold the 45 opposite ends of said plate in firm contact with its rest.

9. In a device of the class described, in combination, a face-plate having two holes therein, a shouldered dowel-pin fitting in 50 one of said holes, a screw-post in the other hole, a nut on said screw-post next to the face-plate and of the same thickness as the shoulder of said dowel-pin, a metal contact-segment having holes in its ends receiving 55 the end of said dowel-pin and of said screw-post respectively, said contact-plate having normally a slight convexity, and a second nut engaging the threaded end of said screw-post above said contact-segment and 60 adapted upon drawing up to flatten said convexity and depress the opposite end of the contact-segment upon the shoulder of said dowel-pin.

In witness whereof I have hereunto set 65 my hand in the presence of two witnesses.

WM. H. GAULKE.
